ROTARY SWAGING OR FORGING MACHINES

Samuel Smith, Elmdon, England

Application November 22, 1950, Serial No. 197,016

Claims priority, application Great Britain
December 2, 1949

4 Claims. (Cl. 78—22)

1

The present invention has relation to rotary swaging or forging machines adapted for hot forging or swaging of round and non-round bars, points, tangs, spikes and the like, more particularly those of the type in which a stationary spindle or central die head is provided with radially displaceable die blanks which are acted upon by a rotatable flywheel or like device mounted upon the spindle or central die head with the intermediary of a plurality of circumferentially disposed rollers, and the present invention has for its object to provide such a machine of generally increased efficiency and utility.

According to the present invention there is provided a machine of the type aforesaid incorporating a plurality of rollers certain of which are recessed the arrangement being such that certain non-recessed rollers shall operate the displaceable dies whilst other recessed rollers shall pass inoperatively over complementary dies the dies thereby being actuated alternately in pairs during the operation of the machine. Conveniently four die blanks with associated hammer blocks may be mounted in the slots in the stationary spindle or die head in right angle relationship and twelve rollers may be used in the track alternate rollers being grooved so that two aligned dies are actuated simultaneously by non-grooved rollers whilst grooved rollers pass over the remaining two hammer blocks, these last being struck when the first mentioned dies have done their work.

In order that the invention may be clearly understood and readily carried into practice reference may be had to the appended explanatory drawings in which:

Figure 1 illustrates in vertical sectional elevation the pertinent part of a rotary swaging machine constructed according to the present invention and

Figure 2 is a vertical section elevation through the machine taken at right angles to the plane of Figure 1.

In a convenient embodiment of the present invention there is provided a rotary swaging or forging machine having a stationary spindle or die head *a* which is cross slotted at *a*¹ (Figure 2) for the reception of dies *b*, hammer blocks *b*¹ and wedges *c* well known in the art. Surrounding this stationary spindle or die head *a* intermediate of the rollers *d*, *d*¹ is a rotatable flywheel *e* or like device, the arrangement being such that on the rotation of the flywheel *e* the rollers *d* operate the dies, which in turn shape the article. In the present invention the rollers *d*, *d*¹ are journaled at *d*² in the rotatable flywheel

e or they may contact each other without end journals *d*² and each alternate roller *d*¹ is grooved, as shown, so that it operates in its track in the normal manner but misses the hammer blocks *b*¹ whereas other alternate rollers *d* are plain and strike the hammer blocks *b*¹. Twelve rollers are advantageously utilised, as illustrated, to fill or substantially fill the track so that when two plain rollers *d* are contacting hammer blocks *b*¹ in alignment, grooved rollers *d*¹ are disposed adjacent the hammer blocks at right angles thereto. These latter hammer blocks are contacted in turn by the plain rollers *d* and the grooved rollers come opposite the first mentioned hammer blocks *b*¹; in this manner cross alternating blows are struck by the hammer blocks. Twelve, twenty or twenty-eight rollers may be used as the machine size increases, the rollers being in multiples of four.

In order to restrict the outward movement of the hammer blocks *b*¹ so that they do not foul the non-striker rolls *d*¹ there is inserted a side key or cotter *f* in a suitable slot half of which is in the hammer block *b*¹ and half in the head *a*, the side cotter extends from front to back of the hammer and is proportioned so that it restricts the outward throw of the hammer *b*¹. To maintain pressure between the annular rolls and the dies there are interposed taper wedges *c* between the dies *b* and hammers *b*¹. The wedges are controlled from the back end of the spindle by means of an adjustable tubular carrier *c*¹ or alternatively may be pedal operated when used to obtain a steep reduction such as forging the tang on a flat file. In this class of work it is an important feature of this invention that the pressure wedges would be applied only to the pair of dies which make the steep reduction on the tang. The spindle of the machine is hollow and provision may be made to introduce a blast of air from a motor driven blower or centrifugal fan mounted at the rear of the machine in order to expel scale from the machine.

In order to minimize the amount of scale likely to enter the working parts there may be extended the front end of the dies beyond the die retaining plate so that the first impact of the dies on the work breaks the scale which falls clear of the working parts.

I claim:

1. In a device of the class described, in combination, a stationary tubular spindle serving as an axle, said spindle having a plurality of transverse slots, a swaging die, a hammer and an adjusting wedge slidably mounted in each of said slots, a roller raceway surrounding the spindle

and extending axially beyond each side of the transverse slots, a plurality of rollers having cylindrical portions rolling on the raceway, alternate ones of said rollers being spool shaped and the remaining rollers being straight cylinders, a second raceway surrounding and journaled on said plurality of rollers, a flywheel surrounding and carried on the second raceway, said swaging hammers having end portions protruding into the path of the straight cylindrical rollers, whereby all of said rollers serve to journal the flywheel and the straight rollers only cooperate with the swaging hammers.

2. In a device of the class described, in combination, a stationary generally tubular spindle serving as an axle, said spindle having at least one transverse slot, a pair of swaging dies, a pair of hammers, and a pair of adjustable wedges slidably mounted in the transverse slot symmetrically with respect to the axis of the spindle, a roller raceway surrounding the spindle and extending axially beyond each side of the transverse slot, a plurality of rollers having cylindrical portions rolling on the raceway, alternate ones of said rollers being spool shaped and the remaining rollers being straight cylinders, a second raceway surrounding and journaled on said plurality of rollers, a flywheel surrounding and carried on the second raceway, said swaging hammers having end portions protruding into the path of the straight cylindrical rollers, whereby all of said rollers serve to journal the flywheel and the straight rollers only cooperate with the swaging hammers.

3. In a device of the class described, in combination, a stationary tubular spindle serving as an axle, said spindle having more than one diametrical slot, a pair of swaging dies, a pair of hammers, and adjustable wedges mounted in each slot, a roller raceway surrounding the spindle and extending axially beyond each side of the slots, a plurality of rollers having cylindrical

portions rolling on the raceway, alternate ones of said rollers being spool shaped and the remaining rollers being straight cylinders, the total number of said rollers being an odd multiple of the total number of hammers, a second raceway surrounding and journaled on the rollers, a flywheel carried on the second raceway, and means for driving the flywheel, said hammers having portions extending into the path of the straight rollers, whereby all of said rollers serve to journal the flywheel and the straight rollers only cooperate with the hammers.

4. In a device of the class described, in combination, a stationary tubular spindle serving as an axle, said spindle having at least one transverse slot, a pair of swaging dies, a pair of hammers, and adjustable wedges mounted in each slot, a roller raceway surrounding the spindle and extending axially beyond the sides of the slot, a plurality of rollers comprising an even number of straight cylindrical rollers alternating with an even number of spool shaped rollers and all running on the raceway, said hammers having portions extending into the path of the straight rollers to be operated thereby, a second raceway journaled on the plurality of rollers, a flywheel mounted on the second raceway and means for driving the flywheel, whereby said swaging dies are operated by the passage of the straight rollers and all of said rollers cooperate to support the flywheel.

SAMUEL SMITH.
